UNITED STATES PATENT OFFICE.

JOHN H. ROYALL, OF HOUSTON, TEXAS, ASSIGNOR OF TWENTY-FOUR ONE-HUNDREDTHS TO G. W. E. MEREWETHER, OF DALLAS, TEXAS, AND TWENTY-FOUR ONE-HUNDREDTHS TO J. R. MAXFIELD, OF WACO, TEXAS.

THERMOSTAT.

1,166,081.

Specification of Letters Patent. Patented Dec. 28, 1915.

Application filed August 3, 1914. Serial No. 854,620.

To all whom it may concern:

Be it known that I, JOHN H. ROYALL, a citizen of the United States, residing at Houston, in the county of Harris and State of Texas, have invented certain new and useful Improvements in Thermostats, of which the following is a specification.

My invention relates to a new and useful thermostat, and its object is to provide a device that will be positive and automatic in its action, closing an electric circuit (which may include an alarm signal) when the temperature of the instrument is abnormally raised, the instrument being further adapted in a slightly modified form to also indicate by closing an electric circuit a temperature below a given standard.

It is another object of my invention to provide a device of the character described, that will be strong, durable, simple and efficient and comparatively inexpensive to produce, and also one that will not be likely to get out of working order.

With these and various other objects in view, my invention has relation to certain novel features of the construction and operation, an example of which is described in the following specification, and is illustrated in the accompanying drawing, wherein:

Figure 1 is a front view of my thermostat, a portion of its casing being broken away to reveal the construction underlying the same. Fig. 2 is a bottom view of the thermostat, the bottom wall of the casing being removed to show the interior construction. Fig. 3 is a vertical sectional view taken upon the line $x-x$ of Fig. 1. Fig. 4 is a horizontal sectional view on $y-y$ of Fig. 1. Fig. 5 is a fragmentary plan view showing a modified form of my invention. Fig. 6 is a view similar to Fig. 2 showing the modification. Fig. 7 is a detail perspective view, showing the mounting of a certain spring embodied in my invention.

Referring now more particularly to the drawing, wherein like reference characters designate similar parts in all the figures, the numeral 1 denotes the rectangular base of my instrument, in which are formed apertures 1^a to receive the screws, whereby said base may be vertically mounted upon a wall. Upon said base respectively adjacent to each corner is mounted an angular bracket com-

prising parts 2, 3 and 4, the parts 2 and 3 being respectively contiguous with the front and bottom of the base, while the part 4 projects forwardly. Between the lugs 4, there are extended two oppositely bowed springs 5 and 6, the extremities of said springs being formed with tongues 6^a which engage in suitable slits formed in said lugs 4. The uppermost spring 5 is bowed toward the base plate 1, and the lowermost of the springs is bowed from said plate. An electrical conductor 7 passing through an orifice 8 in the plate 1 has contact with one of the members 2 as is shown clearly in Fig. 1.

Midway between the extremities of the spring 5, there is surmounted upon said spring a U-shaped bracket 9, said bracket being secured to the spring 5 by a clamping member 10 (see Fig. 7). Between the upstanding side pieces of the bracket 9, there is extended a pin 11, upon which is loosely mounted a bearing 12 rigidly secured to the lower end of an elongated vertical spring 13. The spring 13 projects at its lower end a short distance below its point of pivotal support, and this end is held permanently in contact with the front surface of the spring 6 by a leaf-spring 13^a mounted upon the base-plate 1 behind the spring 13, and exerting a light forward pressure upon the lower end of said spring 13. The upper or free end of the spring 13 is normally slightly spaced from the head of an adjusting screw 14 mounted in a binding post 15 secured upon the base-plate 1 adjacent to its upper edge. The base-plate 1 and the mechanism mounted thereupon are inclosed within a perforated casing 16 secured to the member 1 by a pair of screws 17, the front of the casing being held in its proper spaced relation to the base plate by spacing sleeves 18.

When the temperature of the two springs 5 and 6 is raised, there will be an expansion of said springs proportionate in its magnitude to the increase of temperature. The adjustment is such that when the temperature of said springs is raised to a higher degree than could possibly result from atmospheric conditions, the expansion of the springs 5 and 6 will shift the centers of said springs respectively to and from the base 1, the pivotal point of the member 14 being

thus carried toward the base while its lower end is shifted from the base. This will result in a slight angular displacement of the member 13 sufficient to bring its upper end 5 into contact with the adjusting screw 14, thereby closing the electric circuit, one wire 19 of which comes through the orifice 8 with the other wire 7 and makes connection with the binding post 15. The casing 16 is 10 perforated in order that the atmosphere within the casing may be readily affected by the rise of temperature in the atmosphere exterior to the casing.

If it be desired to use my thermostat to 15 close an electric circuit when the temperature of the instrument falls below a certain point, the lower indicating spring will be bowed toward the base 1 and the upper spring bowed from said base as is indicated 20 at 20 and 21 respectively in Figs. 5 and 6. In this instance the lower end of the member 13 will be pivotally supported upon the lower spring 20, and just above its pivotal point, said member 13 will have contact with 25 the rear face of the spring 21. This construction being followed, it is obvious that the members 20 and 21 in contracting tend to shift the pivot point of the member 13 from the plate 1 and the point of contact of 30 said member 13 with the spring 21 is shifted toward said base plate. By properly adjusting the screw 14, the upper end of the spring 13 will come into contact with said screw when the temperature of the instrument 35 is lowered to a certain degree.

The invention is presented as including all such modifications and changes as properly come within the scope of the following claims.

40 What I claim is:

1. A thermostat, comprising a pair of adjacently mounted oppositely curved bowed springs held against longitudinal movement,

the distance between the ends of each spring being constant, of an elongated circuit closing member having one extremity pivoted upon one of said bow springs at the middle thereof, said member having contact adjacent to its pivoted point with the center of the other bow spring, a spring acting on 50 said member maintaining such contact, a terminal normally spaced from the free end of the closing member, and a circuit normally broken between said terminal and the circuit closing member, a slight relative motion between the two bow springs serving 55 to close said circuit.

2. A thermostat, comprising a base plate, a pair of spaced brackets rigidly secured to said plate, a pair of adjacent oppositely curved bow springs distended between said brackets and held against longitudinal movement therein, a bracket secured to one of said bow springs at its center, an elongated circuit closing member transverse with 60 said bow springs, one of its ends being pivotally supported in said bracket, said member being contiguous with the other bow spring at the center thereof, a spring acting upon the circuit closing member maintaining it in the specified relation, a terminal normally spaced from the free end of said member, a circuit normally broken between said terminal and the circuit closing member, a slight relative motion between the 65 center portions of the bow springs subjecting the circuit closing member to an angular motion bringing its free end into contact with said terminal.

In testimony whereof I have signed my 80 name to this specification in the presence of two subscribing witnesses.

JOHN H. ROYALL.
